UNITED STATES PATENT OFFICE.

ELIZABETH L. BOTTs, OF BUTTE, MONTANA.

SCHOOL-LOOM.

1,181,728.

Specification of Letters Patent.

Patented May 2, 1916.

Application filed October 21, 1914. Serial No. 867,759.

To all whom it may concern:

Be it known that I, ELIZABETH L. BOTTs, a citizen of the United States, and a resident of Butte, in the county of Silverbow and State of Montana, have invented a new and Improved School-Loom, of which the following is a full, clear, and exact description.

The object of the invention is to provide a new and improved school loom, more especially designed for use in schools to teach children the rudiments in the art of weaving, and to permit of weaving tubular fabrics, single or double with flat fabrics, two flat fabrics and the like in various colors and materials.

In order to accomplish the desired result, use is made of a pair of heddles each having a transversely row of apertures alternating with vertical slots, the warp threads passing through the apertures in one heddle, passing through the slots in the other heddle, and vice versa, hand-controlled means for alternately raising and lowering the heddles, a lay slideable forward and backward in front of the heddles for guiding the warp and for beating in the weft, a breast beam, a cloth beam, one or two warp beams, and separator boards intermediate the rear heddle and the said warp beams, each separator board having apertures through each of which passes a corresponding pair of warp threads.

A practical embodiment of the invention is represented in the accompanying drawings, forming a part of this specification, in which similar characters of reference indicate corresponding parts in all the views.

Figure 1 is a sectional side elevation of the school loom, the section being on the line 1—1 of Fig. 2; Fig. 2 is a front view of the same; Fig. 3 is a reduced sectional plan view of the lay on the line 3—3 of Fig. 1; Fig. 4 is a front elevation of one side of the same and showing the guideway for the lay in section on the line 4—4 of Fig. 1; Fig. 5 is a reduced face view of one of the heddles; Fig. 6 is a sectional side elevation of one of the beams and the means for holding the beam against turning; Figs. 7 to 10 are diagrammatic views of the various weaves produced by the loom; Fig. 11 is a side elevation of a modified form for raising and lowering the heddles, the latter being shown in section; and Fig. 12 is a hori-

zontal section of one of the separator boards taken through the apertures.

The loom is mounted on a suitably constructed frame A provided with legs A³ to permit of conveniently supporting the loom on a desk, table, or other support. In the general construction, as shown in Figs. 1 and 2, the loom is provided with two warp beams B, B' located one above the other at the rear of the loom and from the said warp beams unwind two sets of warp threads C, C' passing through openings in the separator boards D, D' to then pass through the heddles E, E' and the lay F to the front of the machine, at which the ends of the warp threads are attached to a cross rod G temporarily held on top of a breast beam H. The rod G is connected by cords I with a rod J temporarily attached to the cloth beam K to permit of winding up the woven fabric, as hereinafter more fully explained.

The warp beams B, B' are provided at one end with handles B³, B⁴ for turning the warp beams, and the latter are further provided on their peripheral faces with recesses B² (see Fig. 6) spaced equal distances apart and adapted to be engaged by the free ends of hooks L pivoted on the corresponding side of the main frame A. On lifting the hook L the warp beam B or B' can be turned to let off the warp C or C' and then the hook L is returned to engage the recess B² now on top with a view to lock the warp beam against rotation. Each of the separator boards D, D' is provided with a transverse row of apertures D², and through each aperture passes a pair of warp threads, it being understood that the separator boards are only supported by the corresponding warp and held adjacent the corresponding warp beam B or B'.

Each of the heddles E, E' is in the form of a plate provided with spaced vertical slots E² terminating a distance from the upper and lower ends of the plate, the slots forming narrow strips E³ on the plate. The strips are provided with rows of apertures E⁴, E⁵ and E⁶ located one above the other. Of a pair of warp threads passing through an aperture D², one of the threads passes through a slot E² in the heddle E and then through an aperture E⁴, E⁵ or E⁶ of the other heddle E', and the other warp thread of this pair of warp threads passes through an aperture E⁴, E⁵ or E⁶ in the heddle E.

and then passes through the corresponding slot E^2 in the front heddle E' . It will be noticed that by this arrangement, one, two or three sets of warps can be accommodated at one and the same time. As shown, use is made of the lower and upper rows of apertures E^4 and E^8 to accommodate the two warps unwinding from the warp beams B and B' . If a third set of warp threads is employed, use is made of the other row of apertures E^5 . The upper and lower ends of the heddles E and E' are provided with cross bars E^7 , E^8 engaging guideways A' , A^2 arranged on the inner faces of the sides 15 of the main frame A so that the heddles E and E' are guided in their alternate up and down movement. The upper ends of the heddles E and E' are connected by links N and N' with a board N^2 provided with bearings N^3 engaging a pivoted rod N^4 extending transversely and attached at its ends to the sides of the main frame A . The links N and N' are connected to the board N^2 at opposite sides of the pivoted rod N^4 , and 20 the said board N^2 is provided at one side with a handle N^5 under the control of the operator to rock the board N^2 with a view to raise one heddle while lowering the other or vice versa. The handle N^5 is adapted to 25 be held in lowermost position by engaging it with a pin N^6 on the corresponding side of the frame A to hold the heddle E in raised position while the heddle E' is held in lowered position. When it is desired to 30 change the position of the heddles E and E' , the operator takes hold of the handle N^5 and slightly swings the same to one side to move out from under the pin N^6 to allow the operator raise the handle N^5 with a 35 view to lower the heddle E and to raise the heddle E' . The handle N^5 is now engaged with the top of a pin N^7 located above the pin N^6 to hold the heddles in the changed position for the time being. It is understood that the handle N^5 is sufficiently 40 resiliency to allow of bending it to one side to disengage the pins N^6 , N^7 prior to swinging the handle up or down as the case may be. Instead of the mechanism described for 45 operating the heddles, as shown in Figs. 1 and 2, use is made of bands O connecting the upper ends of the heddles with each other and extending over a drum O' journaled in the sides of the main frame A . The drum O' is provided with a handle O^2 50 adapted to be swung upward or downward by the operator for turning the drum O' with a view to alternately raise or lower the heddles E , E' . The lay F is provided with a reed F' in the form of a plate provided with vertical slots for the passage of the warp threads to keep the same properly spaced and to allow of beating in the weft C^2 , as hereinafter 55 more fully explained. The reed F' is at-

tached to bottom and top bars F^2 , F^3 , of which the bar F^2 is provided near the ends with slots F^4 extending from the lower edge upward (see Fig. 4) to straddle guideways A^3 formed on the sides of the main frame 70 A . The top and bottom bars F^2 , F^3 are connected with each other at the sides by end bars F^5 to give the desired rigidity to the reed and to the bottom bar F^2 , and to the side bars F^5 are secured rearwardly extending handles F^6 adapted to be taken hold of by the operator for sliding the lay F forward or backward on the guideways A^3 for beating in the weft C^2 and returning the lay F to normal rearmost position in the 80 front of the front heddle E' .

The breast beam H is removably held in vertical guideways A^4 forming part of the main frame A , and on the top edge of the breast beam K is temporarily secured a rod G by the use of tying strings G' , as shown in Figs. 1 and 2. The forward ends of the warps are looped around the rod G to permit the operator to pass the weft C^2 through the open shed of the corresponding 90 set of warps C or C' . It is understood that after the weft is passed through the open shed of each warp C , C' then the lay F is moved forward to beat in the weft C^2 and is then returned to rearmost position, after 95 which the heddles E , E' are changed, as above explained. The weft is then again passed through the open shed and then beaten in, after which the heddles are again changed, and this operation is repeated 100 until a length of fabric has been woven extending close to the lay F when in rearmost position. When this has been done the tying strings G' are untied or otherwise removed, and then the cloth beam K is turned 105 to wind up the strings I , and then the rod G is drawn downward and with it the portion of the fabric woven until the forward end of the fabric is close to the top of the breast beam H . The above-described operation is then repeated, that is, another portion of the fabric is woven, after which the cloth beam K is again turned to wind up the cloth on the cloth beam K , the rods G and J being dispensed with as well as the 110 strings I after the cloth has reached and been wound once or twice around the cloth beam K . The rod J is temporarily held on the cloth beam K by tying strings J' and the rod J abuts against the ledge K' , the ledge extending transversely on the peripheral face of the cloth beam K as shown in section in Fig. 1 and in dotted lines in Fig. 2. Thus when the cloth beam K is turned in the direction of the arrow a' the rod J is carried around by the cloth beam to wind up the strings I . The rods G and J project beyond the side edges of the cloth wound on the beam K and can therefore be 115 readily removed when desired. One outer 120

end of the cloth beam K is provided on its peripheral face with recesses K² spaced equal distances apart and adapted to be engaged by the free end of a hook K³ fulcrumed at K⁴ on the main frame A so that the cloth beam K is held against return movement. The cloth beam K is provided at one end with a handle K⁵ to permit the operator to readily turn the cloth beam K in the direction of the arrow a' whenever it is desired to wind up the woven fabric, as before mentioned.

The weft C² may be of any suitable material to suit the fabric to be woven and the said weft is preferably wound or attached to a board P, which serves as a shuttle, to permit of passing the weft through the open shed from one side of the loom to the other, as previously explained. It will be noticed that by the arrangement described, a single warp may be used for weaving a flat fabric, as shown in Fig. 7, or two warps C and C' may be used for independently weaving two separate flat fabrics, as shown in Fig. 8, or the two warps may be used and the weft passed through first one open shed and then back through the other open shed and returned in a similar way to weave a single flat fabric of double width, as will be readily understood by reference to Fig. 9. In a like manner the weft may be passed alternately through the open sheds of the two warps to weave a tubular bag-like fabric, as indicated in Fig. 10.

Thus from the foregoing it will be seen that the loom can be readily manipulated by school children to learn the rudiments of the art of weaving to permit of weaving different fabrics as mentioned.

The loom shown and described is very simple and durable in construction and can be readily manipulated by children without the slightest danger of injury to them while weaving.

The loom although primarily intended for use in schools may be used in other institutions and in the home. The warps and wefts may be in the form of colored or non-colored threads, yarns, ribbons, bands and the like, and as various forms of weaves can be produced it is evident that a large variety of different textile goods may be manufactured on the loom.

Having thus described my invention, I claim as new and desire to secure by Letters Patent:

1. A school loom comprising a frame, a warp beam journaled in the frame, a pair of heddles having guided movement in the frame, hand controlled means for alternately raising and lowering the heddles, a separator board intermediate the rear heddle and the warp beam and through each aperture of which passes a pair of warp threads, a manually operated lay mounted to slide on

the frame in front of the heddles and provided with a reed, a breast beam on the frame for the passage of the woven cloth, and a cloth beam on the frame for winding up the woven cloth.

2. A school loom provided with a main frame having vertical guideways, a breast beam removably held in said guideways, a rod adapted to rest on top of the breast beam and to which the ends of the warp threads are attached, and means for temporarily fastening the said rod in place on the breast beam.

3. A school loom, comprising a frame, a warp beam mounted on the frame, a pair of manually operated heddles in the frame, a manually operated lay mounted to slide on the frame in front of the heddles, a breast beam, a rod removably secured to the breast beam and with which the warp threads are engaged, a manually operated cloth beam, and a connection between the cloth beam and the said rod for drawing the said rod with the woven fabric down to permit of it being wound on the said cloth beam.

4. In a school loom, a main frame, a pair of heddles, an overhead rocking member journaled in the said frame, links connecting the said heddles with opposite sides of the said rocking member, a handle on the said rocking member, and spaced pins on the said frame and adapted to be engaged by the said handle to lock the heddles in the adjusted position.

5. In a school loom, a breast beam, a transverse rod temporarily attached to the peripheral face of the said breast beam and adapted to be engaged by the warp, a cloth beam, a transverse rod temporarily attached to the peripheral face of the said cloth beam, and flexible connections between the said rods.

6. In a school loom, a main frame provided with horizontal guideways, a lay having bottom and top members, the bottom member being provided with slots engaging the said guideways, side members connecting the top and bottom members, and handles extending rearwardly from the side members to permit the operator to slide the lay forward and backward on the said guideways.

7. A loom, comprising a main frame, warp beams journaled in the said frame one above the other, separator boards having apertures each for the passage of a pair of warp threads, a pair of heddles mounted to move up and down alternately in opposite directions, each heddle frame having vertical slots and transverse rows of apertures for the passage of the warp threads, a lay slideable on the said frame in front of the said heddles and having a reed for the passage of the warp threads, a breast beam on the said frame for the passage of the woven

cloth, and a cloth beam on the said frame for winding up the woven cloth.

8. A loom, comprising a main frame, warp beams journaled in the said frame one above the other, separator boards having apertures each for the passage of a pair of warp threads, a pair of heddles mounted to move up and down alternately in opposite directions, each heddle frame having 10 vertical slots and transverse rows of apertures for the passage of the warp threads, manually controlled actuating means for alternately raising and lowering the heddles, means for temporarily locking the said 15 actuating means in either position of the

heddles, a lay slideable on the said frame in front of the said heddles and having a reed for the passage of the warp threads, a breast beam on the said frame for the passage of the woven cloth, and a cloth beam 20 on the said frame for winding up the woven cloth.

In testimony whereof I have signed my name to this specification in the presence of two subscribing witnesses.

ELIZABETH L. BOTTS.
